UNITED STATES PATENT OFFICE.

FRED E. RANNEY, OF GREENVILLE, MICHIGAN.

DESIGN FOR A HINGE.

SPECIFICATION forming part of Design No. 24,707, dated September 24, 1895.

Application filed August 23, 1895. Serial No. 560,291. Term of patent 3½ years.

To all whom it may concern:

Be it known that I, FRED E. RANNEY, a citizen of the United States, residing at Greenville, in the county of Montcalm and State of Michigan, have invented a new and original Design for Hinges, of which the following is a specification.

This invention relates to a new and original design for hinges, and it has for its object to provide a design of this character that shall be both useful and ornamental.

The leading feature of the design resides in one leaf or member of the hinge having at an intermediate point an inclined portion, at one side of which inclined portion the leaf or member is provided with superficial opposite diagonally-arranged scroll-shaped figures, and at the other side of which inclined portion the hinge leaf or member is provided with an L-shaped extension having irregularly-scalloped edges, the vertical portion of which L-shaped extension is provided with opposite diagonally-arranged scroll-shaped figures, and the horizontal portion of which L-shaped extension is provided with superficial lines or ridges forming leaf-like figures, and the other hinge leaf or member having superficial lines forming leaf-like figures and oppositely-disposed lanceolar projections curved toward each other.

In the drawings, Figure 1 is a plan view of an ornamental hinge embodying the herein-described design. Fig. 2 is a longitudinal sectional view of the same.

Referring to the drawings, the numeral 1 designates an ornamental hinge essentially consisting of the separate leaves or members 1 and 2, respectively. In the present invention the hinge leaf or member 1 is provided at an intermediate point with an inclined portion 3, at one side of which portion 3 the face of the leaf or member is provided with superficial opposite diagonally-arranged scroll-shaped figures 4. At the other side of the inclined portion 3 the leaf or member 1 is provided with an L-shaped extension 5, having an irregularly-scalloped edge 6. The vertical portion of the L-shaped extension 5 is provided with opposite diagonally-arranged scroll-shaped figures 7, and the horizontal portion of the extension 5 is provided with superficial lines or ridges forming leaf-like figures 8. The other hinge leaf or member 2 is provided with superficial lines forming leaf-like figures and oppositely-disposed lanceolar projections 9, curved toward each other.

What is claimed is—

The design for an ornamental hinge herein shown and described.

In testimony that I claim the foregoing as my own I have hereto affixed my signature in the presence of two witnesses.

FRED E. RANNEY.
